(57) **CLAIM**

The ornamental design for a novelty mailbox, as shown and described.

DESCRIPTION

FIG. 1 is an environmental perspective in a closed position of a first embodiment of a novelty mailbox showing our new design;

FIG. 2 is a front elevational view thereof;

FIG. 3 is a rear elevational view thereof;

FIG. 4 is a right side elevational view, with the left side being a mirror image, thereof;

FIG. 5 is a top plan view thereof;

FIG. 6 is a bottom plan view thereof;

FIG. 7 is an environmental perspective in an open position thereof;

FIG. 8 is an environmental perspective in a closed position of a second embodiment thereof;

FIG. 9 is a front elevational view thereof;

FIG. 10 is a rear elevational view thereof;

FIG. 11 is a right side elevational view, with the left side being a mirror image, thereof;

FIG. 12 is a top plan view thereof;

FIG. 13 is a bottom plan view thereof; and,

FIG. 14 is an environmental perspective in an open position thereof.

The broken line showing of the flag indicator and the post in FIGS. 1, 7, 8, and 14 is for illustrative purposes only and forms no part of the claimed design.
